UNITED STATES PATENT OFFICE.

GEORGE M. BROX AND HOWARD S. KNIGHT, OF MILFORD, NEBRASKA.

SPIKE.

1,106,622.

Specification of Letters Patent. Patented Aug. 11, 1914.

Application filed May 24, 1913. Serial No. 769,666.

To all whom it may concern:

Be it known that we, GEORGE M. BROX and HOWARD S. KNIGHT, citizens of the United States, residing at Milford, in the county of Seward and State of Nebraska, have invented new and useful Improvements in Spikes, of which the following is a specification.

Our present invention pertains to spikes, and more particularly to spikes designed to 10 be driven into wood with a view to securing railroad rails and other objects thereto.

The object of our invention is to provide a spike for use in wood, constructed in such manner that the cost of producing the spike 15 is not materially increased, and yet the spike is adapted through the medium of an ordinary nail to be securely locked or anchored in the wood.

With the foregoing in mind the invention 20 will be fully understood from the following description and claim when the same are read in connection with the drawings, accompanying and forming part of this specification, in which:

25 Figure 1 is a perspective showing our novel spike with the anchoring nail properly positioned therein. Fig. 2 is a view, partly in elevation and partly in section, of the same. Fig. 3 is an elevation of the nail *per se*.

Similar numerals of reference designate corresponding parts in all of the views of the drawings.

The improved spike comprises a shank 1, and a head 2, which may be and preferably are of the conventional configuration, though they may be of any other suitable shape compatible with our invention without departure from the scope of the same as claimed. The head 2 overhangs at least one side of the shank 1, as indicated by 2^a in Figs. 1 and 2. In furtherance of our invention, there is formed in the said overhanging portion 2^a of the head 2 and in the adjacent 45 side of the shank a vertical kerf 3. This kerf 3 is straight and extends from the upper side of the head 2 to a point adjacent the lower end of the shank. At the latter point the kerf merges into and communicates with 50 one end of a downwardly inclined bore 4 which extends transversely through the shank to the opposite side thereof.

As will be readily appreciated the portion of the kerf in the overhanging head portion 2^a is much deeper than the alined or registered portion of the kerf in the side of

the shank; and it will also be appreciated that the said kerf can be so readily formed in the spike as not to materially or in fact appreciably increase the cost of producing 60 the spike. It will also be noted here that the upper portion of the said kerf 3 extends inwardly into the main portion of the head 2—*i. e.*, the head portion, that is alined with the shank.

In using the spike described the same is driven home in a sleeper or tie or other body of wood. With this done a headed nail 6 is driven down through the kerf 3 of the spike until the head 7 of the nail brings 70 up against the upper side of the spike head 2. When the nail is thus driven it will be guided by the kerf 3 to that end of the transverse bore or passage 4 in registration with said kerf, and hence the lower portion 75 of the nail will be caused to pass through the bore or passage 4 and to project from the side of the spike opposite to that in which the kerf 3 is formed. It will also be observed that by reason of the point of the nail contacting with the bottom wall of the bore 4, the portion of the nail that protrudes from the side of the spike shank will be directed outwardly and upwardly from the shank. By virtue of this the said end 80 portion of the nail will securely anchor the spike in the wooden body and will effectively prevent casual loosening or outward working of the spike, and in this the said end portion of the nail will be materially 85 assisted by the superposing of the nail head 7 on the spike head 2.

It will be readily understood from the foregoing that after the spike has been driven until its head 2 brings up against the 95 wooden body, the kerf formed in the overhanging portion of the spike head and in the major portion of the head will enable the operator to expeditiously and easily guide the point of the nail into registration 100 with the upper end of the kerf portion that is formed in the spike shank, and by reason of this the accurate driving of the nail is facilitated.

Having described our invention, what we 105 claim and desire to secure by Letters-Patent, is:

The herein described spike, consisting essentially of a shank and a head integral with the shank and having a portion that 110 overhangs one side of the shank and is provided with an underside disposed at a right

angle to the shank, the shank having a transverse bore at an intermediate point in its length and also having a vertical kerf in its said side, of even depth throughout its length, registered and communicating with the bore at one end thereof and extending from the bore to the inner side of the extended portion of the head, and the head having a vertical kerf that extends throughout the height of its overhanging portion, said kerf extending into the major portion of the head and having its inner portion in

alinement and communication with the kerf in the shank and also having its outer side open throughout its width and height.

In testimony whereof we have hereunto set our hands in presence of two subscribing witnesses.

GEORGE M. BROX.
HOWARD S. KNIGHT.
